FIG. 2

FIG. 3

INVENTOR

Eugene W. Zipf.

By Walter J. Macklin,
ATTORNEYS

UNITED STATES PATENT OFFICE.

EUGENE W. ZIPF, OF MINERAL RIDGE, OHIO.

CLOSURE SEAL.

Application filed May 5, 1922, Serial No. 558,688. Renewed May 16, 1925.

To all whom it may concern:

Be it known that I, EUGENE W. ZIPF, a citizen of the United States, residing at Mineral Ridge, in the county of Trumbull and State of Ohio, have invented a certain new and useful Improvement in a Closure Seal, of which the following is a full, clear, and exact description, reference being had to the accompanying drawings.

This invention relates to seals for containers and includes also a method of sealing containers, such as barrels, tubes, and the like.

One of the methods heretofore employed for sealing barrels, particularly those adapted for containing liquid material has embodied the use of a plug which is threaded into a wall of a receptacle or barrel, and is provided with an opening through which the customary wire of a car seal may be threaded. In shipment, however, such seals are frequently broken whenever the barrels are stored one above another; and in addition, the position of the opening in the removable member with relation to that of the stationary member is not always best for convenient application of the car seal.

One of the objects of my invention, therefore, is the provision of a seal which not only insures ample protection to the consignee, against surreptitious or unauthorized opening of the container, but also permits the storage of one container above another without damage to the seal.

My invention includes not only the seal, but also the method of attaching the seal, as will be hereinafter described in connection with the drawings forming a part hereof. The essential features will be summarized in the claims.

In the drawings, Fig. 1 is a plan view of a closure member adapted for use with my invention; Fig. 2 is a similar view showing a seal for the closure; Fig. 3 is a vertical section taken transversely through the closure and container as shown in Fig. 2.

My invention is particularly well adapted for use on barrels or steel containers which are used for holding oil or other liquid material, and accordingly, I have shown a portion of such container at 10. The wall of the container may be provided with an annular member 11 which may be threaded, as at 12, to receive a plug 13.

In practice this annular member is usually 55 welded to the wall of the container so as to provide a fluid-tight joint therewith, as illustrated in Fig. 3, and is provided with a flanged portion 14, which is in abutting engagement with the outer surface of the 60 wall 10.

To seal the plug or closure 13, I have shown a seal 20 in the form of a thin metal strip which may have the name of the consignee stamped therein, if desired. This 65 strip is shown as having an opening at each end thereof for engaging the upstanding portions 21 on opposite sides of the flange 14. The upstanding portions are adapted to be riveted over the strip, for securely 70 holding it in place after it is extended over the closure. In this way, the strip is in close fitting engagement with the closure, and is thus protected against inadvertent displacement by contact with another 75 container or other object while in transit. The upstanding portions are preferably formed integral with the annular member 11.

From the foregoing description, it will be seen that a seal constructed according 80 to my invention may be quickly attached to a container, and be permanently held thereon even though subjected to the usual rough handling incident to shipments of this character. Since the strip lies flat against the 85 closure and is somewhat flexible, it may be bent in contact with another object, but the manner of attachment is such that there is very little tendency for such contact to strip the seal from the container. Furthermore, the construction employed 90 enables the seal to be attached to all forms of containers without necessitating expensive construction which tends to increase the cost of manufacture. 95

Having thus described my invention, I claim:

1. In combination, a container having a threaded opening therein, a threaded closure in engagement with the opening, a 100 strip of metal extending across the top of the closure, members extending upwardly from the container on each side of the closure and projecting through said strip, said members being permanently attached to the 105 strip whereby the turning of said closure automatically ruptures said strip.
2. In combination, a container, an annu-

lar member rigidly secured thereto, said member having a flanged portion extending around the periphery thereof, and having a threaded opening adjacent the central portion thereof, a closure for said opening, a pair of upstanding portions on opposite sides of said flanged portion, and a strip of light sheet metal extending across the clo-

sure and having the ends thereof permanently attached to said upstanding portions, whereby turning of said closure automatically ruptures said strip. ¹⁰

In testimony whereof, I hereunto affix my signature.

EUGENE W. ZIPF.
